UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

HEADER.

1,194,452.

Specification of Letters Patent. Patented Aug. 15, 1916.

Application filed December 17, 1914. Serial No. 877,756.

To all whom it may concern:

Be it known that I, RICHARD LESTER WILCOX, a citizen of the United States, residing at Waterbury, in the county of New Haven and State of Connecticut, have invented certain new and useful Improvements in Headers, of which the following is a specification, reference being had therein to the accompanying drawings.

10 My invention relates to a new and improved header, and has particular reference to the punch shifting and feed mechanisms thereof.

The punch shifting mechanism as disclosed herein is applicable to a type of header requiring a plurality of blows to produce the desired results, while the feed mechanism is adapted to any header and any form of mechanism requiring a reliable feed.

15 It is the object of this invention, among other things, to produce a header with a friction feed that may be operated without the use of a pawl, as is common in mechanisms of this character, and wherein the punch shifting mechanism and feed devices are operated from a single cam, that are adjustable both as to the extent of movement 20 of the punch slide and the length of feed by elements located upon the outside of the machine, where they are readily accessible and easily manipulated, to provide simple and positive mechanism for stopping the feed, as well as means for controlling the same so 25 that it will be impossible to feed except at the proper time, and means for assuring always a full length feed.

To these, and other ends, my invention 30 consists in the header, having certain details of construction and combinations of parts as will be hereinafter described and more particularly pointed out in the claims.

Referring to the drawings, in which like 35 numerals of reference designate like parts in the several figures, Figure 1 is a side elevation of my improved header; Fig. 2 is a fragmentary longitudinal section thereof through the gate and crank, showing a side elevation of the punch slide and the punch block with the punches therein; Fig. 3 is a 40 enlarged front view of the punch slide, block and punches, with the rock shaft and shifter arm thereon; Fig. 4 is a sectional view of the shifter arm, taken upon line

A—B of Fig. 1; Fig. 5 is a fragmentary 55 plan view of the connecting link, with portions of the mechanism immediately adjacent to the ends thereof; Fig. 6 is a fragmentary plan view of one end of the header, with the feed mechanism connected therewith; Fig. 7 is an enlarged sectional view of the parts, taken upon line C—D of Fig. 6; Fig. 8 is an enlarged sectional view of the parts, taken upon line E—F of Fig. 7; Fig. 9 is an enlarged sectional view of the 65 parts, taken upon line G—H of Fig. 7; and Fig. 10 is a detail view of the link block 70 adjusting mechanism.

In the mechanism herein described, I so combine the several parts that both the 70 shifting of the punch slide and the feeding of the wire is derived from the operation of a single cam. This is a new feature in headers, and as a result thereof the number of parts is very materially reduced, with all the 75 advantages that result therefrom, both as to economy of construction and maintenance, as well as simplicity of operation. Adjustments are provided so that the length of the stroke of the punch slide and the length of 80 the feed may be varied as desired.

The feed mechanism is constructed without the use of a pawl and ratchet, friction devices being substituted therefor, and elements movable in the path of said friction 85 devices are provided to release their grip and stop the feed. This latter feature is controlled from a handle that is mounted upon a fixed part, its position thereby being always substantially the same and materially enhancing the convenience of its operation as distinguished from the type of pawl mechanisms above referred to, wherein the pawl usually moves about the axis of the pawl disk and must be grasped while in 90 motion. In the latter form it is apparent that the more rapid the feed, the more difficult it is to grasp and operate the continually moving pawl. This handle can only be operated at such times as will insure a full 100 length feed, but if desired, the feed may be stopped instantly. The length of the stroke of the feed mechanism is adjustable, means being provided for accomplishing this through a coarse adjustment and a fine adjustment, either one or both of which may be dispensed with if desired.

In the drawings the numeral 1 designates

the body of the machine supported upon legs 2 and within which is rotatably mounted the crank shaft 3 having a fly wheel 4 and a pinion 5 thereon, which latter meshes into and imparts motion to a gear 6 fixed upon a shaft 7 rotatably mounted in the underside of said body. Slidably mounted within the body 1 is the gate 8 that is connected with the crank shaft 3 by the connection 9. All 10 of the parts just described are common and well known in the art and require no additional description or illustration herein. Slidably mounted within the gate 8 is a punch slide 10, having a punch block 11 fixed thereon and within which is secured the punches 12 and 13.

My invention is shown herein as applied to what is known as a double stroke header, that is, one requiring two successive blows 20 to complete the upsetting operation, although it may be applied to a header having a greater number of blows if desired.

The wire to be operated upon is presented in front of the punches with its axis substantially coincident with the line 14 that is located upon one side of the feed line 40, and in substantially the same horizontal plane. As the gate 8 moves forward the slide 10 is moved within the said gate at substantially 30 a right angle to the movement thereof so that the punches 12 and 13 are successively presented with the axes thereof coincident with the line 14. This step by step movement of the punch slide is derived from a cam 15 fixed on the shaft 7, which imparts a rocking movement to the shaft 16 through the shifter arm 17, either integral therewith or fixed thereon, as may seem most desirable, through a shifter connection 18 having 40 rolls 19 and 20 thereon in contact with the periphery of said cam. An adjustable connection between said shifter connection and shifter arm is provided, comprising a stud 21, having a block 22 thereon, that slides 45 within the opening 23 in the shifter connection 18, and a washer 24 held in place by a nut 25 to prevent movement of said block within the opening 23. Said stud passes through an opening 26 in the shifter arm 17 and is adjustable through a screw 27 held 50 against endwise movement by a pin 28, a washer 29 and a nut 30 locking said stud 21 to the washer arm 17 when in its adjusted positions. The relative position of the block 55 22 within the shifter connection 18 is determined by the position of the stud 21 within the opening 26 of the shifter arm 17, and the same is locked in any of its positions by the screws 31 and 32 which impinge against the 60 opposite ends of the said block. It is obvious that the closer the stud 21 is moved toward the center of the shaft 16, the shorter the movement of the rock shaft 16, and vice versa, thereby providing means for varying 65 the position and length of stroke of the

punch slide. It will be observed that all of the mechanisms necessary to accomplish this adjustment are upon the outside of the machine, are readily accessible, and easily controlled.

The immediate connection between the rock shaft 16 and slide 10 comprises a yoke 33 preferably formed integral with the shaft 16, and within which is pivotally mounted a slide block 34 upon the studs 35 fixed in said yoke; and a foot plate 36 secured to the lower end of the slide 10 by the screw or bolt 37, and movable within the slide block 34.

During the rocking movement of the shaft 80 16, derived as above indicated, through the cam 15, connection 18 and shifter arm 17, the studs 35 travel about the axis of said rock shaft, rising and falling as the result thereof, and as the block 34 is pivotally connected therewith, the movement is transmitted to the punch slide 10 through the foot plate 36, which slides through the block 34 during its forward and backward movement.

The upward movement of the punch 10 occurs as the shifter arm is moved to the right, as shown in Fig. 1, at which time the strain is upon the cam, and the down movement of the cam slide 10 occurs when said shifter arm is moving to the left, this movement being accelerated by the weight of the slide, punch block and all of the parts connected therewith, so that there is practically no strain upon the cam.

The dies are designated by the numeral 38 and have a lateral movement within the body 1 through the reciprocating action of the plate 39 by means not herein shown or described, and travel so that the grooves in the meeting faces thereof pass from the line of the wire feed, designated 40, to the line of the heading operation, designated by the numeral 14. The dies are held against the plate 39 and returned to the line 40 by mechanism comprising the plate 41 connected to the ends of the slidably mounted rods 42, having a head bracket 43 thereon, against which is the end of a spring 44 secured at its opposite end to the body 1 by a cap 45. A screw 46 threaded through the head bracket 43 and abutting against the bed 1, limits the inward movement of the parts just described.

Pivotedly secured within the stud 47 is 120 the trip latch 48 having trip arms 49 and 50 thereon, through the latter of which is an adjusting screw 51 that lies within the path of movement of the head bracket 43. This latch is subject to the pressure of a 125 spring 52 that bears against the end of a pin 53 contacting with the arm 49 and actuates the said latch to move the trip arm 49 away from the body 1.

Connected with the body 1 is a roll frame 130

54, within which is rotatably mounted the shafts 55 and 56, each of which is provided with a feed roll 57 and intermeshing gears 58 and 59. In one face of the gear 59 is a 5 ring 60 and concentric therewith is a clutch plate 61 secured thereto by screws 62, and having a plurality of notches 63 in the edge thereof, said notches having roll faces 64 and end faces 65. Within each of said 10 notches is a roll 66 that is moved in one direction between the face 64 and the inner face of the ring 60 by a pin 67 having a head 68 thereon with an angular face which contacts with the roll 66. A spring 69 pressing against the end of the pin 67 provides a yielding pressure against the roll 66.

Rotatably mounted upon the roll shaft 56 is a trip head 70 having the offset arm 71 integral therewith, within which is mounted 20 the block 72 that is adjustable through a screw 73 threaded therein and rotatable within the trip head 70 with a spiral gear 74 thereon which meshes into a spiral gear 75 fixed upon a shaft 76 rotatable in the trip 25 head 70 through a knob 77 fixed upon the outer end thereof. The position of the knob 77 is so relatively close to the center of the shaft 56 that its circular movement is very limited and it may be readily rotated 30 during the movement of the trip head 70 to vary the radial position of the block 72 within the arm 71. A link 78 that connects the shifter arm 17 and block 72 is secured to the latter by a pin 79 and to the former by 35 a pin 80, which is held against accidental disengagement by a catch plate 81 rotatably secured to the link by a screw 82 and which enters a groove 83 in the pin 80. The length of stroke of the link 78 is varied by shifting the 40 point of connection thereof with the shifter arm 17, this being accomplished by passing the pin 80 through any one of a plurality of holes 84 in the said shifter arm. This adjustment is generally known as a coarse adjustment. The fine adjustment of the feed 45 is determined by the radial position of the block 72 within the offset arm 71, which, as above described, is secured by rotation of the knob 77.

50 As the shifter plate 17 moves to the left, as shown in Fig. 1, the trip head 70 is moved in the direction shown by the arrow in Fig. 7, at which time the clutch 61 (which is fastened to the trip head 70) moves the 55 rolls 66 against the faces 64, assisted by the action of the pins 67 and springs 69 so that the rolls impinge between the inner surface of the ring 60, causing a frictional engagement between all of the parts. The ring 60 will now rotate, and through it, the gear 59, with which it is connected, which rotation in turn is transmitted to the gear 58, shafts 56 and 55 to the rolls 57, causing the same to impart an endwise feed movement to the wire therebetween. Upon the

reverse movement of the shifter arm 17, the trip head 70 is moved in the opposite direction, and the clutch 61, having faces 64, contacts with the periphery of each of the rolls 66 and moves them against the heads 70 68, and the tension of the spring 69. The effect of this action is to break the connection therewith so that the trip arm rotates freely without imparting movement to the feed mechanism.

Immediately upon the movement of the shifter arm 17 being reversed from that last described, the friction hold of the rolls 66 between the clutch 61 and the ring 60 takes place, and all of the parts move with the motion of the trip head 70. With the arrangement of operation outlined there is practically no additional strain upon the shifter arm 17 from the feed mechanism while it is moving to the right in Fig. 1, at which time the work required of the cam 15 through the action of the slide 10 is the greatest, and the reverse is also true, that when the shifter arm 17 is moving to the left the strain thereon and upon said cam 90 is greatest from the feed. Therefore, the work upon the cam and shifter arm is uniformly distributed and the punch shifting mechanism and feed mechanism operate in perfect harmony, that is,—when the strain 95 thereon, by reason of the operation of the punch mechanism, is the greatest, it is the least from the feed mechanism, and vice versa.

The mechanism for stopping the feed 100 operation comprises a disk 84, which is rotatably mounted upon the trip head 70, with one face thereof against the face of the ring 60 (see Fig. 8), and inclosed within an overhanging lip 86 upon the gear 59. Fixed 105 within this ring are a plurality of release pins 87, corresponding in number with the rolls 66, and projecting into the path of movement thereof and lying between the clutch face 64 and the ring 60. The center 110 of these release pins 87 are more distant from the center of the shaft 56 than that of the rolls 66, so that as they engage the said rolls they have a tendency to force the same against the face 64 and away from the inside of the ring 60.

Rotatably mounted upon a stud 88 fixed in the trip head 70, is a release arm 89, that is connected with the disk 84 through the pin 90, and having a roll 91 rotatably 120 mounted upon one end thereof. A spring 92 connected at one end to a pin 93 in the outer end of the offset arm 71, and at the other end to the pin 90, always exerts its tension so as to rock the release arm 89 upon 125 its pivot mounting and move the disk 84 upon its axis so as to force the release pins 87 into contact with the rolls 66.

Pivotedly secured to the body 1 upon the stud 94, is a roll arm 95, which is connected 130

with a handle 96 by the link 97. The handle 96 is provided with a tail piece 98, and is rotatably mounted upon a fixed stud 99. In Figs. 1 and 7 the roll arm 95 is shown in such position that the curved portion or sweep thereof is concentric with the axis of the shaft 56, in which position the roll 91 rides against its inner face, being held there by the spring 92. While the parts are in these relative positions the disk 84 moves with the trip head 70 as a unit, and the release pins 87 and rolls 66 occupy the relative positions substantially as shown in Fig. 7.

To move the rolls 66 so as to prevent them having a frictional engagement with the clutch 61 and ring 60, the handle 96 is moved upon its pivot mounting to the position shown by broken lines in Figs. 1 and 7 which brings the roll arm 95 to the position shown by broken lines in Fig. 1, wherein the curved portion or sweep thereof is eccentric to the axis of the shaft 56.

The spring 92 still maintains the roll 91 in contact therewith, but while moving to this latter position, the release arm 89 is moved upon its pivot mounting and an independent movement is given to the disk 84 through the pin 90 and the release pins 87 are moved against the rolls 66, which shift and break their frictional engagement between the clutch face 64 and the ring 60. So long as the roll arm 95 occupies the last described position, the shafts 56 and 55 remain stationary and no feed movement is transmitted to the rolls 57. When the handle 96 is in the position shown by full lines in Fig. 1, the trip latch 48 is in the position shown by broken lines in Fig. 6, at which time it will be observed that the screw 51 in the end of said latch is out of the path of movement of the head bracket 43, the trip arm 49 being held against the tail piece 98 by the spring pressed pin 53. It is therefore impossible to discontinue the feed operation when the parts are in this relative position.

When the handle 96 is moved to the position shown by dotted lines in Fig. 1, against the stop pin 101, the tail piece 98 has moved to such a position that it is engaged by the notch 100 in the outer end of the trip arm 49, which is then moved by the spring pressed pin 53 to the position shown by full lines in Fig. 6 and effectually locks said handle 96 against further movement until the trip latch 48 is released. This is done at the next movement of the head 43, which engages the end of the screw 51 and rocks the trip latch and moves the same out of the path of the trip arm 98, and the handle 96 can now be again operated so as to re-establish the feeding operation. It will be observed, that with this device, instead of the operator attempting to catch a fast moving handle to throw the feed in or out, as is

the case with the ratchet and pawl mechanism in common use, it is only necessary for him to grasp a conveniently located stationary handle that is always in the same relative position. The handle 96 can be moved from its full line position to its dotted line position in Fig. 1, at any time, irrespective and regardless of any other part. The operator, however, is not at liberty to throw the handle 96 into a feed position until the correct time, this being determined and controlled by the position of the dies. When the handle 96 is in the feed position (full lines, Fig. 1), it cannot be moved farther to the right, as the square end 102 of the link 97 abuts against the end face of the slot in the said handle (see Fig. 7), and the center of the pin 85 is slightly beyond the dead center sufficiently to hold it in position and resist any strain upon the roll arm 95 by the contact of the roll 91 thereon.

There are minor changes and alterations that can be made within my invention, and I would therefore have it understood that I do not limit myself to the exact construction herein shown and described, but claim all that falls fairly within the spirit and scope of the appended claims.

Having described my invention, what I claim as new and desire to secure by Letters Patent, is:

1. In a header, the combination with a cam; of a movably mounted punch block; a feed mechanism for presenting stock in line with said punch block; and means for actuating said block and feed mechanism from said cam.

2. In a header, the combination with a cam; of a movably mounted punch block; a feed mechanism for presenting stock in line with said punch block; and means for actuating said block and feed mechanism from said cam through a rock member.

3. In a header, the combination with a punch block; of a feed mechanism for presenting stock in line with said punch block; a rocking member; a connection between said rocking member and punch block; a connection between said rocking member and said feed mechanism; and cam means for actuating said rocking member.

4. In a header, the combination with a movably mounted punch block; of a feed mechanism for presenting stock in line with said punch block; a rock member, means for operating said punch block and feed mechanism from a single member, said means having the maximum operating strain thereon from only one of said elements, that is, said punch block and feed mechanism at a time, and cam means for actuating said rock member.

5. In a header, the combination with a movably mounted punch block; of a feed mechanism for presenting stock in line with

- said punch block; an intermediate rock shaft; an operative connection between said rock shaft and punch block; a cam; an operative connection between said cam and 5 rock shaft whereby movement is imparted thereto; and a connection between said rock shaft and said feed mechanism whereby movement is imparted thereto.
6. In a header, the combination with a 10 movably mounted punch block; of a feed mechanism for presenting stock in line with said punch block; an intermediate rock shaft; a positive connection between said rock shaft and punch block; a shifter arm 15 connected with said rock shaft; a cam, an operative connection between said cam and shifter arm whereby movement is transmitted from said cam to said rock shaft; and a connection between said shifter arm 20 and feed mechanism.
7. In a header, the combination with a 25 movably mounted punch block; of a feed mechanism for presenting stock in line with said punch block; an intermediate rock shaft; a shifter arm connected with said rock shaft; a cam, an operative connection between said cam and shifter arm, whereby movement is transmitted from said cam to
- said rock shaft; means for adjustably securing said connection; a connection between said shifter arm and feed mechanism; and means for adjustably securing the last mentioned connection to said shifter arm. 30
8. In a header, the combination with a punch block; of a rock shaft; means for 35 actuating said rock shaft; and a rotary and slidable connection between said punch block and rock shaft, comprising a slide block rotatably connected with said rock shaft and a foot plate slidably within said 40 slide block and connected with said punch block.
9. In a header, the combination with a punch block; of a rock having a yoke connected therewith; a slide block pivotally 45 mounted in said yoke; a slide; a foot plate connected with said slide and having an operative connection with said slide block; and a punch block connected with said slide.

In testimony whereof I affix my signature 50
in presence of two witnesses.

RICHARD LESTER WILCOX.
